CLAIM

The ornamental design for a combined key ring and extendable, self-defensive baton, as shown and described.

DESCRIPTION

FIG. 1 is a right side elevational view of a combined key ring and extendable, self-defensive baton showing my new design, the left side being a mirror image thereof;

FIG. 2 is a top plan view thereof, the bottom being a mirror image thereof;

FIG. 3 is a front elevational view of FIG. 2; and, FIG. 4 is a rear elevational view thereof.
